UNITED STATES PATENT OFFICE.

EDWARD LEWIS DALES, OF PHILADELPHIA, PENNSYLVANIA.

ELECTRIC-LIGHTING FIXTURE.

Application filed March 9, 1922. Serial No. 542,435.

To all whom it may concern:

Be it known that EDWARD LEWIS DALES, a citizen of the United States, residing at Philadelphia, in the county of Philadelphia and State of Pennsylvania, has invented certain new and useful Improvements in Electric-Lighting Fixtures, of which the following is a specification.

My invention relates to electric lighting fixtures.

The principal object of the invention is to provide a fixture of the class stated wherein two reflectors are utilized, viz:—a horizontal reflector at the top of the fixture and a reflector surrounding the lamp, constituting a two piece electric lighting unit, this unit being associated with a combined socket cover and support for the lower reflector, the support being capable of vertical adjustment to secure the proper distribution of light.

A further object of the invention is to provide a cup shaped reflector to be placed over the lower end of the lamp to serve as an additional light shield, when required.

A still further object of the invention is to provide a fixture of the class described wherein the diameter and contour of the horizontal reflector at the top thereof, combined with the diameter and height of the lower reflector are so proportioned as to secure a graded distribution of light without definite shadow.

Other objects and uses of the invention will appear from a detailed description of the same, which consists in the features of construction and combinations of parts hereinafter described and claimed.

In the accompanying drawings forming a part of this specification, and in which similar reference characters indicate like parts in each of the views:—

Figure 1 is a side elevational view, partially in section, of a two piece lighting unit, embodying my invention;

Figure 2 is an inverted plan view thereof. Referring in detail to the drawing, the fixture, as an entirety, is designated by the character A, and comprises a horizontal reflector *a*, shown in the drawing mounted on a tripod B, adapted to be connected to the electric outlet in the ceiling, or where an outlet box (not shown) is provided on the ceiling, then such tripod B may be connected therewith by any suitable means, such, for instance, as a nipple and whatever ad-

ditional parts, i. e., joint, hickey, etc., that may be required by the conditions of the electric outlet. There should, however, be no appreciable space between said reflector *a* and the ceiling, in order that no halations or shadows may be cast thereon by said reflector.

A threaded nipple C provided in the base of the tripod B is designed for engagement with one end of a short pipe D, the lower end whereof passes through an opening in the upper portion of a metal socket cover F and has a threaded engagement with a standard commercial lamp socket E, into which is adapted to be threaded an electric lamp or bulb H having a threaded upper portion G thereto for such purpose.

The socket E is wired for electrical current in accordance with the requirements of the electric outlet in the ceiling.

The horizontal reflector *a* also serves as a canopy to cover the electric outlet.

The socket cover F is adapted to act as a support for the horizontal reflector *a*, and the lower reflector M is suspended therefrom by means of supports I, shown in the drawing as three, but they may be of whatever number required for the purpose; the lower portions J of said supports I being threaded and secured in brackets K provided on the upper portion of said reflector M by means of nuts L, whereby vertical adjustment may be made of said reflector M which surrounds the lamp H. The means for suspending said lower reflector M from the socket cover F, however, may be varied without departing from the salient features of my invention.

The horizontal reflector or canopy *a* is constructed with the convex portion A' on its outer surface, to reflect the light rays cast thereagainst and it may be constructed either of metal or glass. When made of glass, with the surface broken up by sand blasting or other means to produce a light diffusing surface, the inner surface may be colored and decorated and the outer surface oiled, resulting in an unique and pleasing effect both in appearance and lighting values.

I prefer to fashion the convex portion A', of the reflector *a*, in the form shown, namely, that said portion A' shall have a greater diameter than the largest diameter of the lower reflector M, whereby the beams of light from the lamp H will, upon striking

the curved surfaces thereof, be widely radiated into the room, or apartment and thus augment the lighting properties of the lamp.

The lower reflector M, surrounding the lamp H, is constructed of sheet metal with an efficient reflecting surface on the inside exposed to the direct rays of the lamp H; the outside to be colored and decorated.

The socket cover F is designed to fit over 10 the standard commercial lamp socket.

The horizontal reflector a also serves to illuminate the outside surface of the lower reflector M.

When it is desired to further shield the 15 eyes of the beholder from the direct light rays from the lamp H, lamps of the type of Mazda C-4, with frosted or enameled tip may be used. To completely shield the eyes from the direct rays from said lamp H, a 20 sheet metal cup N, conforming to the contour of the larger and lower end of the lamp H is positioned thereover. This cup N is supported in place by three or more wire 25 clips P. An opening O in the base of said cup N permits the passage of the pointed end H' provided on the usual commercial type of lamp.

One of the wired clips P is in turn wired 30 by a wire Q to one of the supports I of the lower reflector M, so that the cup may be removed from the lamp, for the removal or replacement of said lamp or to clean the fixture, or other purpose, without removing said cup N entirely from the fixture.

35 The inside of the cup N is to be provided with an efficient reflecting surface. The outside thereof to be colored as required by the finish of the fixture. By the use of this cup N the fixture partakes of an indirect lighting type, while without its use the fixture is more or less a semi-indirect lighting type.

In the foregoing detailed description I have disclosed an electric lighting fixture having several features of novelty and 45 utility, such as, a lighting fixture comprising a horizontal reflector which acts as a canopy; the use of glass for this horizontal reflector—with a diffusing surface and colored or otherwise decorated, mainly on the 50 inside and oiled on the outside; a vertical metal reflector in connection with said horizontal reflector, dimensioned to produce a graded illumination without shadow, receiving reflected light on its outside surface 55 from the horizontal reflector and arranged for vertical adjustment; a means for entirely concealing the direct light rays of the lamp by using a third reflector over the tip of the lamp; a fixture, simple and economical in construction which because of the ar-

rangements and proportions of its parts is pleasing en masse; a fixture which will not decrease in efficiency by use because of dust collecting on its surfaces; a fixture which is easily cleaned with a minimum of breakage; 65 an indirect lighting fixture which delivers a large proportion of the illumination provided by the lamp; a fixture easily installed and a fixture which can be readily decorated and therefore lend itself for use in any surroundings, i. e., commercial use, where illuminating efficiency is the main consideration, or as part of the decoration of an artistic interior.

Obviously minor modifications, not involving invention, may be made in the construction of the fixture without departing from the spirit of my invention or the scope of the appended claims.

Having thus described my invention what 80 I claim as new and desire to secure by Letters Patent is:—

1. An electric light fixture, comprising in combination, a horizontal reflector convex on its outer surface, a lamp socket, a lamp secured in said socket, a socket cover supporting said reflector and a reflector suspended from said socket cover and surrounding said lamp, said horizontal reflector being made of glass with its outer surface 90 broken up to produce a light diffusing surface and the inner surface thereof being decorated, substantially as described.

2. An electric light fixture, comprising in combination, a horizontal reflector convex on 95 its outer surface, a lamp socket, a lamp secured in said socket, a socket cover supporting said reflector, a reflector suspended from said socket cover and surrounding said lamp, a cup conforming to the contour of the lower and larger portion of said lamp and adapted to fit thereover and means to retain said cup in position on said lamp to divert the direct rays from said lamp, substantially as described.

3. An electric light fixture, comprising in combination, a horizontal reflector convex on its outer surface, a lamp socket, a lamp secured in said socket, a socket cover supporting said reflector, a reflector suspended from said socket cover and surrounding said lamp, a cup conforming to the contour of the outer lower portion of said lamp and adapted to fit thereover, clips to retain said cup in position on said lamp and means to 110 secure one of said clips to the suspending means from said socket cover to said lower reflector, substantially as described.

In testimony whereof I affix my signature.
EDWARD LEWIS DALES.
